UNITED STATES PATENT OFFICE.

HENRY G. STEINBRENNER, OF CLEVELAND, OHIO, ASSIGNOR, BY MESNE ASSIGNMENTS, TO INDUSTRIAL BROWNHOIST CORPORATION, A CORPORATION OF OHIO.

MEANS FOR CONTROLLING THE DRIVING GEAR OF LOCOMOTIVE CRANES.

Application filed August 6, 1927. Serial No. 211,135.

My invention relates to means for connecting and disconnecting the driving gear of locomotive cranes so that in the one instance it will be a self-propelling unit and the other instance its running gear will only function as idlers as in ordinary railroad rolling stock.

When locomotive cranes are shipped from the factory to their destination by rail on their own wheels it is necessary to disengage the travel gear and mechanisms from the truck axles, inasmuch as the speed at which the train, of which the locomotive crane is then a part, is much greater than the designed speed of the locomotive crane under its own power, and, the mechanisms would otherwise be wrecked. Of course, the same conditions prevail when a locomotive crane is hauled out on the main lines or right-of-way by locomotives for repair or construction work.

A principal object of my invention, therefore, is to provide a means for quickly and positively disengaging the gearing from the driven axles of locomotive cranes under these circumstances, and, without endangering the persons who make such disengagements.

Heretofore, in locomotive cranes, the driven bevel gears, located on the truck axles have been of the split (two halves) type securely clamped to the axles in mesh with the bevel pinions on the longitudinal transmission shaft. When it became necessary to disengage the gears it was necessary for a mechanic to crawl under the crane and unfasten the bevel gears from the axles, slide them along the axles away from and out of mesh with the bevel pinions on the longitudinal transmission shaft, and then re-clamp the gears to their axles in their then out-of-mesh positions.

To obviate danger to the life or limb of mechanics in such adjustments, later designs have incorporated loose gear and jaw-clutch arrangements for the truck axles. In this type the jaw-clutch is slidably keyed to the axle and the axle turns freely in the bevel gear which is held from rotating by the bevel pinion. The jaw clutch is operated from the side of the crane by a screw-and-nut arrangement. This scheme is a decided improvement over the first one, but is expensive to build and adds a considerable sum to the cost of the crane.

It is accordingly another object of my invention to provide a less expensive means for disengaging the bevel gears of locomotive crane trucks. I accomplish this object by moving the bevel pinions out of mesh with their companion bevel gears which are located on the truck axles, thereby dispensing with any special clutching means.

The drawing is a bottom view of two trucks of a locomotive crane coupled together with the usual transmission gearing and embodying my present invention. The left hand truck shows the engaged relation of the parts and the right hand truck the disengaged relation.

T and T' are trucks that support the car-body (not shown) of a locomotive crane with their pivotal points located on the median line of the same, as at P and P', respectively. The axis of rotation R of the crane's superstructure is also located on the median line M, midway of the pivotal points P and P'. Both trucks are equipped with idler axles I, I, and, driven axles D and D' which are mounted in track-wheels W.

Bevel gears B and B' are mounted, respectively, on and near the centers of axles D and D', with their faces or teeth toward the median line M, and are securely keyed and fastened to said axles. Integral collars or shoulders, c, c are preferably located on the axles immediately behind the gears B and B' to provide against any lateral displacement of the gears.

Bracket, or G shaped castings, G, G' are slidably mounted on and carried by the axles D and D', respectively. In the drawing these parts are shown as having three points of bearing-contact with the axles, namely, one at each extremity 1 and 2 of the castings, and one, 3, midway thereof. At these points bearing-caps, are provided, within and through which the axles extend. When the mechanisms are assembled, the straight, or closed side, of the castings in each case, will be on the same side of the axle as the axis of rotation R, and the castings themselves will connect the bearings 1 and 2 and include between these points, respectively, the gears B and B'. A sleeve or hub-like portion p, of the castings carrying the bearing-contact 3 at its inner end extends inwardly around the axles to the median line M. At right angles to the axis of the bearings 3, and at the same elevation, are bearings 4 on the

sleeves, and directly opposite thereto in said castings, and in line therewith, are, severally, bearings 5. In the castings are mounted stub-shafts S, S, extending from the bearings 4 and through bearings 5, far enough to accommodate and become operatively engaged at their outer ends, respectively, to universal couplings K and K.

Fixedly mounted on the stub-shafts S, S, between the bearings 4 and 5, are bevel-pinions B², adapted to mesh with the bevel-gears B and B', respectively, with their faces toward the axles.

A triple-bearing TB, supporting a longitudinal power-transmission shaft L, is indicated as extending downwardly from the center of the car-body (not shown). The shaft projects far enough beyond its supporting bearings b, b, of the triple-bearing TB, to accommodate the ends of universal couplings K', K'. The complementary end members of the universal couplings K, K, and K', K' are operatively connected by shafts S' S'.

A bevel gear g is mounted on the longitudinal shaft L between the bearings b, b, with its face toward the center of rotation R. It is driven by a bevel pinion g' at the lower end of a vertical shaft V.

The castings G, G' are provided with lever supporting fins F, F which are located on the loop-portion of the casting opposite the bearings 2, 2. A bifurcated lever H with its bifurcated end embracing the fin F is pivotally connected to the latter at f. The lever is provided with a pin hole h near the pivotal point f and also with a lug l at one side near its pivotal end, said lug l also having a hole. The fins F, F are also provided with holes h', h² for the purpose to be explained, hereinafter.

The axles D and D' are turned down to shorter diameters at points about midway of the bearings 2, 2 and the track wheels W, W, to accommodate split collars SC, SC that are loosely mounted to allow the axles to rotate. Toggle-links t and t', arranged in parallel pair-members, (one at the top and the other at the bottom) are pivotally connected at one of their ends to the bearings 2, 2, and the split-collars SC, SC, respectively. The stem ends of yokes Y, Y are pivotally bolted to the lugs l, l of the levers H, H and the yoke portions extend above and below the axles D and D' and are pivotally connected to the other, or free, ends of the pairs of toggle-links t, t'.

It will be readily seen, upon referring to the drawing, that, by manipulating the lever H of the left-hand truck assembly, in the direction indicated by the arrow A, until the hole h in the lever registers with the hole h² in the fin F, the toggle joints will

be broken and the casting G, carrying the pinion B², will slide along the axle D' until the bearing 1 contacts with the collar e, thereby disengaging the bevel-pinion B² from the bevel-gear B. A bolt may be passed through the registered holes h and h² to hold the lever in place.

To engage the bevel-pinion B² with the bevel gear B the lever H of the right hand truck assembly is manipulated in the direction indicated by the arrow A', until the hole h in the lever registers with the hole h¹ of the fin F, whereupon the casting G will slide along the axle D until the bearing 1 reaches a shoulder O on the axle D. The gears are held in mesh, positively, by placing a bolt into the registered holes h and h¹.

What I claim and wish to protect by Letters Patent, is:—

1. In combination with the driven axle of the truck of a locomotive crane, a bracket-like part, or casting, slidably connected at its ends to the same, a bevel-gear fixedly mounted on the axle between the points of said connection, with its face, or teeth, fronting toward the median line of the truck, a journal, in line with and jointedly coupled to the power-transmission shaft of the crane, extending through and within said bracket-like part in bearing contact with the same and in front of the bevel-gear, a bevel-pinion adapted to mesh with said gear, fixedly mounted on said journal, and means for reciprocating said part along said axle to an extent to carry said pinion in or out of mesh engagement with said bevel-gear, substantially as shown and described.

2. A driving-gear for the trucks of locomotive cranes, or similar structures, comprising a bracket-like part, or casting, provided with an inwardly projecting sleeve-like portion or hub, at one end, and a corresponding bearing at the other end in slidable engagement with the driven axle of the truck through said hub and bearing, a bevel gear fixedly mounted on the axle between said engagement parts, with its face, or teeth, fronting toward the median line of the truck, a journal, in line with and jointedly coupled to the power-transmission shaft of the crane, extending through and within said bracket-like part in bearing contact with the same, and in front of said bevel-gear, a bevel pinion, adapted to mesh with said gear, fixedly mounted on said journal, and means for reciprocating the bracket-like part along said axle to an extent to slide said pinion in or out of engagement with said bevel-gear, substantially as shown and described.

In testimony whereof I hereunto affix my signature.

HENRY G. STEINBRENNER.
